UNITED STATES PATENT OFFICE.

HARVEY L. MILLER, OF LEAVENWORTH, KANSAS, ASSIGNOR TO CHARLES W. PARKER,
OF LEAVENWORTH, KANSAS.

CAROUSEL.

1,121,748.

Specification of Letters Patent. Patented Dec. 22, 1914.

Application filed January 26, 1912. Serial No. 673,532.

To all whom it may concern:

Be it known that I, HARVEY L. MILLER, a citizen of the United States, and a resident of Leavenworth, in the county of Leavenworth and State of Kansas, have invented a new and Improved Carousel, of which the following is a full, clear, and exact description.

My invention relates generally to carousels and more particularly is directed to certain new and useful improvements in such structures wherein the rapid and efficient assembling of the parts is provided, thereby providing a construction which is easily taken apart for transportation, the arrangement, however, being such that the parts when assembled are held together effectively and safely.

The principal object of my invention is to provide new and improved means in the assemblage of parts used in carousels, merry-go-rounds, and hobby-horses of the type in which an up and down movement is imparted to the figures, in addition to the movement around the circumference of a circle.

Other objects and advantages of the invention will appear as the description thereof proceeds, all of which is particularly pointed out and included in the appended claims.

Reference is to be had to the accompanying drawings forming a part of this specification in which similar characters of reference denote corresponding parts in all the views, and in which—

Figure 1 is a side view of a figure commonly used in carousels, the means whereby the up and down movement is imparted to the figure being shown; Fig. 2 is a vertical sectional view of the vertical support showing the means whereby the step is supported in position; Fig. 3 is a horizontal sectional view on the line 3—3 of Fig. 2 showing the means whereby the step is prevented from lateral movement; Fig. 4 is a plan view of the pivoted fork which engages with the bottom of the vertical supporting member; Fig. 5 is a detail view of the coöperating parts at the top of the vertical supporting member for engagement with a crank arm whereby the up and down movement is imparted; Fig. 6 is a side view of the upper end of the structure shown in Fig. 5; Fig.

7 is a vertical sectional view showing the pivotal support, together with the locking means therefor between the bottom of the vertical support and the forward end of the fork shown in Fig. 4; Fig. 8 is a view similar to Fig. 7 but on a plane at 90° thereto; Fig. 9 is a detail view showing the pivotal supporting means for the rear ends of the fork.

Referring particularly to Fig. 1 which embodies the structures herein described and claimed, a figure 1 which is generally a horse or animal, is suitably supported at an intermediate point on the vertical support 2, this support and the figure being adapted to be given an up and down movement through the medium of a crank 3 which engages in suitable mechanism at the upper end of the support; the lower end of this support is in pivotal engagement with the forward end of a fork 4, the rear end of the fork being adapted to be pivoted to a suitable support 5 carried on the floor or base of the rotating structure 6. The vertical support 2 which may be made of any desired material, but preferably of metal, is provided with a suitable collar 7 which engages against the lower face of a lug 8 carried on the under side of figure 1, the support extending through the figure which is provided with a suitable opening, the support being also provided with a suitable step 9 whereby access to the top of the figure 1 is provided. This step is shown in detail in Figs. 2 and 3 and comprises a vertically extending portion 10 having the step proper 90 extending laterally from one end thereof, the upper end of the portion 10 being provided with an offset arm 11 having a hook 12 at the outer end thereof. Adjacent the lower end of the portion 10 is another arm 95 13, preferably shorter than the arm 11, and provided with a hook 14 adjacent its outer end. The support 2 is provided with openings 15 at diametrically opposite points, the openings registering with each other, the arm 11 on the side of the portion 10 of the step being adapted to be entered into these openings with the hook 12 engaging the outside of the support whereby the parts are secured; at a point suitably spaced below 100 one of the openings 15 is another opening 16 into which the arm 13 on the portion 10 of the step is adapted to be seated, it being

noted that the width of these openings is substantially equal to the width of the arms 11 and 13 at the hooked ends so that the arms may be entered therein, the final position of the parts being obtained by giving a slight downward movement to the step in order to bring the hooks 12 and 13 into the position shown in Fig. 2. In order to prevent turning of the step 9 relatively to the support 2, the portion 10 of the step is preferably provided with curved offsets 17 adapted for engagement with the outside of the support as shown particularly in Fig. 3.

Referring particularly to Figs. 5 and 6, it will be noted that the upper end of the support 2 is provided with a hook 18 of any desired construction, the hook being adapted to pivotally support a bearing in which the crank arm 3 is carried so that, as the crank arm turns, the support may move up and down with ample freedom. The bearing comprises two portions 19, 20, through which the crank arm 3 extends, the two portions being suitably secured together by means of bolts and nuts 21, the upper portion 20 of the bearing being provided with arms 22, 23, having suitable openings therein through which a pin 24 extends. The bearing with the crank shaft therein is positioned within the hook 18, the hook itself being provided with a suitable opening through which the before-mentioned pin 24 extends, the pin being retained in these openings in any suitable manner, as by spreading the ends thereof. The lower end of the hook 18 may be secured to the vertical support 2 in any suitable manner consistent with safety and rapid separation, the preferred means being a bolt and nut or screw 25.

Since the support 2 is to oscillate or travel up and down as the carousel is rotated, it is necessary that some structure be provided for engagement with the lower end of the support in order to insure the proper relative position of the parts and to this end I make use of the fork 4, shown particularly in Figs. 1 and 4. This fork comprises the sides 26, the rear ends of which are divergent and terminate in the parallel ends 27, the forward portions 28 being convergent and being held closely together by means of a rivet 29. Each of the ends 27 and on the inner sides thereof is provided with a transversely extending lug 30, the outer end of each lug being provided with a boss 31; secured to the floor or frame 6 of the structure are the supports 5 having up-standing parts 32, each of which is provided with a transversely extending opening 33, there being a recess 33 communicating with each opening whereby (Fig. 9) the lugs 30 may be entered into pivotal relation with the supports 5 when the ends 27 are brought into such position that the bosses 31 may freely pass

through the recesses 33 while the said lugs are entered into the openings 33. The forward converging ends 28 of the fork are in pivotal engagement with the lower end of the vertical support 2 by a structure substantially as follows: Pivotally secured to the outer end of the part 28 is the coupling 40; this coupling is preferably of integral construction and each end thereof is bifurcated whereby a plurality of arms 41, 41', is provided adjacent one end and arms 42, 42' adjacent the opposite end. A pin 43 extends through the arms 41, 41', this pin also engaging a suitable opening in the outer end of the part 28, there being another pin 44 extending between the arms 42, 42', on which a key 45 is pivotally supported between these arms. Referring particularly to Fig. 7 it will be noted that the length of this key is substantially greater than the diameter of the vertical support 2, the pin 44 extending therethrough at a substantially intermediate point; the upper edge portion of the key is curved, as shown in this figure, the coupling being positioned within the vertical support with the key extending transversely thereof and bearing against the lower side walls of openings 46, 47, contained in the support and at diametrically opposite points thereof. It is to be noted that the length of one opening 47 is substantially greater than the length of the other opening 46, the purpose of which provides for easy separation of the parts by an upward movement of the coupling, the end of the key contained within the slot of greater length moving upwardly into the dotted line position of Fig. 7 until the end of the key normally seated within the opening 46 is withdrawn therefrom by engagement with the side walls of the said opening 46, the key being then contained in the interior of the support and in position for convenient withdrawal.

The vertical support 2 being suspended pivotally from the crank arm 3, relative movement of these parts is permitted when the device is in operation and since the lower end of this support 2 is also in pivotal engagement with the floor or frame of the structure, the oscillation or up and down movement of the figure 1, which is mounted on the support 2, is freely permitted, movement, however, of the figure and anybody seated thereon being confined to determined paths so that disengagement of the parts with consequent injury to a rider is prevented.

The carousel construction herein described is especially directed to devices which are transported more or less and hence which require taking apart and packing in a short space of time; the fork 4 which is the connecting link between the bottom of the support 2 and the floor or frame 6 is in pivotal

engagement with these parts at its ends, the key 45 carried by the coupling 40 being easily detached from the support when so desired in the manner set forth; it is to be noted that the fork 4 carries no load and is used to hold the movement of the lower end of the support 2 to a well-defined path.

The material of which the different parts of the device is made will depend upon the size thereof and the load which the different figures are designed to carry as well as the size of the carousel itself, such changes along with those of size and shape being matters of design and comprehended within the spirit of my invention.

Having thus described my invention, I claim as new, and desire to secure by Letters Patent:—

1. The combination of a hollow support having openings therein, with a coupling extending within the support, one end of the coupling being adapted to be pivotally connected to a suitable fork, the other end of the coupling being provided with a pivotally mounted key, the ends of which are engaged in the said openings of the support.

2. The combination of a hollow support with a coupling positioned therein, the said support adjacent the upper end of the coupling being provided with openings at diametrically opposite points, together with a key extending transversely of the support and contained in the said openings, the key being in pivotal engagement with the end of the coupling.

3. The combination of a hollow support having openings at opposite sides thereof, of a coupling having one end portion contained within the support, with a key, the length of which is greater than the diameter of the support, the ends of the key being contained within the said openings, the key being pivotally engaged with the said end of the coupling.

4. The combination of a hollow support having openings at diametrically opposite points, one of the openings being of greater length than the other, a coupling having a portion thereof contained within the support with a key extending transversely of the support and of greater diameter than the support, the ends of the key being contained within the said openings, the key being in pivotal engagement with the said end of the coupling and freely movable thereon whereby when the coupling is given an upward movement through the support, the engagement of the side wall of one of the openings with the key will bring the key into the interior of the support whereby the parts may be separated.

5. In a carousel and in combination with a movable fork therein, a support embodying an upstanding portion having an opening extending therethrough, the upstanding

portion being also provided with a recess communicating with the opening, the recess and the opening being adapted to receive a lug having a boss thereon carried by the fork.

70

6. In combination with a movable fork in a carousel, supports embodying upstanding members, each of which is provided with an opening and each of which is also provided with a recess communicating with the said opening, the said openings and recesses being adapted to receive extending lugs with bosses at the outer ends thereof carried by the said fork whereby the fork may be held in pivotal engagement with the said supports.

75

7. The combination of a hollow support having diametrically opposite openings, a coupling extending within the support, one end of the coupling being adapted to be pivotally connected to a suitable fork, the end of the coupling within the support being provided with a movably mounted key, the ends of the key being engaged in the said openings of the support.

90

8. The combination of a support having a plurality of oppositely-disposed openings therein, another opening in one side of the support, a step having laterally extending arms, each arm having a hook at the free end thereof, one of the arms being of greater length than the other and extending through the said first openings, the second arm extending into the second opening, the hooks of the arms engaging with the adjacent portions of the support, whereby the step is held in position.

95

9. The combination of a support having openings therein, the said openings being oppositely-disposed and registering, another opening in one side of the support suitably spaced from the said first opening, a step having a number of laterally extending arms, the outer end of each arm being hooked, one of the arms being longer than the other, and being entered into the said registering openings, the second arm entering the said second opening, the hooked ends of the arms engaging the sides of the support, whereby the step is held in position.

105

10. The combination of a support having oppositely-positioned and registering openings therein, a step comprising a vertically extending portion and also comprising an arm, the outer end of which is hooked, the said arm entering the said openings, the hooked portion of the arm engaging the side of the support, offsets carried by the step and adapted to extend around closely adjacent the outside of the support, whereby the step is held in position on the support.

110

11. In a carousel, the combination of a vertically extending support, a rotating crank, the end of the support being hooked,

115

a bearing pivotally mounted on the said hooked end, pivotal means comprising a pin extending through the end of the support, and through the bearing, the bearing engaging the said crank, whereby, as the crank is turned, the support will have imparted thereto a reciprocating motion.

In testimony whereof I have signed my name to this specification in the presence of two subscribing witnesses.
